DESIGN FOR A DESK

Erskine Ramsay, Birmingham, Ala.

Application November 18, 1942, Serial No. 108,810

Term of patent 14 years

To all whom it may concern:

Be it known that I, Erskine Ramsay, a citizen of the United States, residing at Birmingham, in the county of Jefferson and State of Alabama, have invented a new, original, and ornamental Design for a Desk, of which the following is a specification, reference being had to the accompanying drawing, forming a part thereof.

In the drawing:

Fig. 1 is a top plan view of a desk embodying my new design;

Fig. 2 is a front elevational view of the same; and

Fig. 3 is an end elevational view thereof.

I claim:

The ornamental design for a desk, substantially as shown.

ERSKINE RAMSAY.
